METHOD OF CHILLING LUBRICATING OILS
FOR DEWAXINGEdward Ellsberg, Westfield, N. J., assignor of
three-fourths to Tide Water Oil Company,
Bayonne, N. J., a corporation of New Jersey

Application August 15, 1931, Serial No. 557,197

4 Claims. (CL 196—18)

It has hitherto been considered that, for the production of low cold test cylinder stocks or long residuums obtained from wax-bearing crudes, by the centrifuge method or other methods, slow chilling at a rate of approximately $2\frac{1}{2}$ ° F. per hour from the solution point of the wax (about 100° F. to 110° F.) down to the temperature at which dewaxing is effected, or at this slow chilling rate down to a temperature of 10° F., followed by somewhat accelerated chilling to the lower final temperature at which dewaxing occurs, is essential to growth of the wax crystal so that in the dewaxing operation it may be settled, centrifuged, or removed by other dewaxing methods.

I have discovered that by proper operation this slow and expensive chilling can be partly or largely eliminated and the dewaxing process greatly improved in capacity and decreased in cost.

Contrary to previous practice and theory, my method consists in taking the mixture of oil to be dewaxed diluted with naphtha, and after heating to such a point that the wax goes into solution, chilling the solution continuously as rapidly as possible to a temperature about one-third to one-half the range through which the solution is to be chilled. The oil being thus chilled well below its cloud point, part of the wax is precipitated out of solution. During this process, this oil may be chilled at the rate of 4° F. per minute instead of $2\frac{1}{2}$ ° F. per hour, which is a chilling rate completely out of the range of previous practice.

At this point, the partly chilled oil is removed from the continuous rapid chillers and run continuously through a series of tank chillers, where the chilling rate is much reduced so that the oil is further chilled at a slower rate, about 2-4° F. per hour. During this slower chilling period, sufficient time is allowed for the gradual growth or formation of wax crystals, so that the oil on emerging from the chilling system will dewax with the same facility in a centrifuge plant or other dewaxing method as if the solution had been chilled by the usual slow chilling.

As a result of this method, it is now possible greatly to reduce the time of process, the cost of equipment, and the cost of chilling over methods previously in use. Approximately half the chilling can be done in inexpensive apparatus in a period of ten minutes, which by previous methods required one hundred times that period, or about 18 hours, and a different type of chilling equipment costing six to ten times as much.

The accompanying drawings illustrate schematically an arrangement of apparatus for carrying out the invention, Fig. 1 being a simplified pic-

torial illustration, and Fig. 2 being a more diagrammatic illustration omitting some parts shown in Fig. 1.

The wax-bearing oil and the diluent are fed from tanks 2 and 3, respectively, in proper proportions, through pipes 4 and 5 to a blending tank 6, where the solution may be heated by means of a heating coil 7. It will be understood that the oil in tank 2 may already be partially diluted. The solution is pumped through shock chillers 8 and then through tank chillers 9, the pipes for this purpose being marked 10 in Fig. 1. From the last tank chiller, the solution may be pumped through piping 11 direct to a centrifuge 12, or to another form of dewaxing apparatus; or through another branch 13, the solution, after passing through part or all of the tank chillers, may be put through one or more final shock chillers 8^a before going to the dewaxing apparatus. The dewaxed oil solution is drawn off at 14 and the wax at 15. The inlet and outlet connections for passing cooling medium through the various chillers are marked 16 and 17 in Fig. 1.

The solution in passage through coils in shock chillers 8 is chilled rapidly from about 100-110° F. down to about 50° F., for example. The solution then passes to the series of tank chillers 3 comprising as many units as are required. In its slow progress through these tanks and around the cooling tubes therein, the solution is chilled through the remainder of the chilling range at the slow rate, and I find that with my process a rate as high as about 4° F. per hour during this period is not too fast and permits of additional saving of time and economy in equipment in respect to this stage of the process. The solution emerges from the final tank chiller at a temperature of about -50° F. and is delivered to the dewaxing treatment. The process is equally effective whether the dewaxing step is effected by centrifuging, by settling, or by filtering.

In Fig. 2 the course of the solution is indicated by the heavy arrows, while the inflow and outflow of cooling medium is indicated by light arrows. The cooling medium may be brine, ammonia or dewaxed oil.

The invention is not necessarily limited to chilling at a substantially steady rate throughout a single slow chilling stage succeeding the shock chilling and carrying the temperature down to the dewaxing point. When the temperature of the solution has been lowered by the gradual chilling down to about 10° F., the rate of chilling may be accelerated with further economy and satisfactory results. Thus, this final chilling may

be accomplished at a rate of about 4° F. per minute in passage through the additional shock chillers 8^a.

I claim:

- 5 1. The method which involves heating wax-bearing lubricating oils diluted with lighter hydrocarbons until the wax goes completely into solution, continuously shock chilling the solution well below the cloud point of the wax, to a temper-
10 ature about one-third to one-half the range of temperature through which the solution is to be chilled, then passing the shock-chilled solution to a further chilling treatment whereupon the rate of chilling is radically reduced to the order 15 of only a few degrees per hour, chilling the solution down to the temperature at which dewaxing is to occur, after which the chilled solution is dewaxed.
2. The method which involves heating wax-
20 bearing lubricating oils diluted with lighter hydrocarbons until the wax goes completely into solution, continuously shock chilling the solution well below the cloud point of the wax, to a temper-
25 ature about one-third to one-half the range of temperature through which the solution is to be chilled, then passing the shock-chilled solution to a further chilling treatment whereupon the rate of chilling is radically reduced to the order 30 of only a few degrees per hour, chilling the solution down to the temperature at which dewaxing is to occur, after which the chilled solution is dewaxed.
- 30 3. For the dewaxing of wax-bearing lubricating oils in solution with lighter hydrocarbons, the method which comprises chilling the solution from a temperature at which the wax is completely in solution to a temperature well below the cloud point of the wax at a rate on the order of about 4° F. per minute, after which the chilling is conducted at a radically reduced rate.

of temperature through which the solution is to be chilled, then passing the shock-chilled solution to a further chilling treatment whereupon the rate of chilling is radically reduced to the order of only a few degrees per hour, gradually 80 chilling the solution to about 10° F., and completing the chilling at an accelerated rate, after which the chilled solution is dewaxed.

3. For the dewaxing of wax-bearing lubricating oils in solution with lighter hydrocarbons, 85 the method which comprises chilling the solution from a temperature at which the wax is completely in solution to a temperature well below the cloud point of the wax at a rate on the order of about 4° F. per minute, after which the chilling is conducted at a radically reduced rate.

4. For the dewaxing of wax-bearing lubricating oils in solution with lighter hydrocarbons, the method which comprises shock chilling the solution from about 100-110° F. to about 50° F., and 90 effecting further chilling at a radically reduced rate.
